US00D963647S

(12) **United States Design Patent** (10) Patent No.: **US D963,647 S**
(45) Date of Patent: ** *Sep. 13, 2022

(54) **MONITOR FOR COMPUTER**

(71) Applicant: **LG ELECTRONICS INC.**, Seoul (KR)

(72) Inventors: **Yongsoo Kim**, Seoul (KR); **Yeonjin Kim**, Seoul (KR); **Daihyung Ryu**, Seoul (KR)

(73) Assignee: **LG ELECTRONICS INC.**, Seoul (KR)

(*) Notice: This patent is subject to a terminal disclaimer.

(**) Term: **15 Years**

(21) Appl. No.: **35/512,800**

(22) Filed: **Apr. 27, 2021**

(80) **Hague Agreement Data**

Int. Filing Date: **Apr. 27, 2021**

Int. Reg. No.: **DM/214023**

Int. Reg. Date: **Apr. 27, 2021**

Int. Reg. Pub. Date: **Oct. 29, 2021**

(30) **Foreign Application Priority Data**

Nov. 27, 2020 (KR) 30-2020-0058242

(51) LOC (13) Cl. **14-02**

(52) U.S. Cl.

USPC **D14/375**; D14/379

(58) **Field of Classification Search**

USPC D14/125-129, 132, 203.3, 203.7, 300, D14/308, 310, 336, 341, 371, 372-380;

D21/330

CPC G06F 1/1601; G06F 1/1605; G06F 1/162
